FIG.1

FIG.2

FIG.3

FIG.4

FIG.5

FIGURE 1 is a front elevational view of a fork showing the essential features of my new design in full lines; the back of the fork handle is substantially plain and follows the contours of the front as shown in FIGURE 1; and

FIGURES 3, 4 and 5 are enlarged cross-sections taken respectively on the lines 3—3, 4—4 and 5—5 of FIGURE 1.

The back of the fork handle is substantially plain and follows the contours of the front as shown in FIGURE 1.

The design is intended for use on spoons, forks, knives and similar articles of flatware.

I claim:

The ornamental design for a fork or similar article of flatware, substantially as shown and described.
